DESIGN FOR A COMBINED PAN COVER AND GRATER

Arthur A. Nu Dell, Chicago, Ill.

Application April 30, 1937, Serial No. 69,068

Term of patent 3½ years

To all whom it may concern:

Be it known that I, Arthur A. Nu Dell, a citizen of the United States, residing at Chicago, in the county of Cook and State of Illinois, have invented a new, original, and ornamental Design for a Combined Pan Cover and Grater, of which the following is a specification, reference being had to the accompanying drawing, forming part thereof. On the drawing, Figure 1 is a top plan view of my new design for a combined pan cover and grater, and Figure 2 is an enlarged cross-sectional view thereof taken generally on the line 2—2 of Figure 1.

I claim:

The ornamental design for a combined pan cover and grater substantially as shown.

ARTHUR A. NU DELL.
